APPARATUS FOR SHIRT OR MERCHANTISE
DISPLAYNoel E. Pool and Fred N. Curby,
Salt Lake City, Utah

Application October 30, 1934, Serial No. 750,616

6 Claims. (Cl. 248—28)

Our invention relates to supporting devices for advertising displays and has for its object to provide a new and efficient apparatus for shirt or merchandise display, which device is adjustable 5 as to size and which is primarily designed to display shirts in show windows.

A further object is to provide an apparatus for a self adjusting device for holding shirts supported on a suitable stiff base in the proper position for showing them to prospective buyers and which device will eliminate the necessity of unpinning new shirts, pinning them over the usual display board, then placing them in the window. Also after they have been displayed these shirts 15 must be refolded to the original manufacturer's form and oftentimes they are dirtied or mussed to such an extent as to not be fit for sale. With our invention the shirt is taken from the box in which it was packed and the two pins removed from 20 the cuffs and a flat board is inserted into the fold of the shirt the board being of any suitable stiff material. The shirt is then pinned onto the board and the support device is then attached to the board to hold the shirt in display position.

The apparatus of the invention relates to a suitable support for this board and to the adjustable features thereof, only one device size being necessary for all shirts, as it is adapted to fit any size shirt fold now being used by 30 shirt manufacturers.

These objects we accomplish with the device illustrated in the accompanying drawing in which similar numerals and letters of reference indicate like parts throughout the several views and as 35 described in the specification forming a part of this application and pointed out in the appended claims.

In the drawing in which we have shown the best and most preferred manner of building our 40 invention,

Figure 1 is a rear view of a shirt set on the stiff support board, with the adjustable bracket placed thereon ready to set the bracket in any suitable window display base.

Figure 2 is a side elevation of the adjustable bracket.

Figure 3 is a face view of Figure 2.

Figure 4 is a side elevation of the device extended on a larger display board to show some of the 50 extent of expansion capable of the bracket with the spring cut away to more clearly show the links.

Figure 5 is a back view of Figure 4.

The apparatus for our invention as shown in the drawing consists of a center support rod 1 having the bottom end turned back upon itself

to form a hook 2 and with the top end 3 carrying diverging pivoted links 4 and 5. These pivoted links 4 and 5 are pivotally secured to the top end of the rod 1 by a pivot pin 6 and these pivoted links carry another set of holding links 7 and 8, by the ends of said holding links being pivoted to the ends of the pivoted links 4 and 5, by pivot pins 9 and 10. The ends of these two holding links 7 and 8 are provided with hooks 11 and 12 similar to the hook 2 of the rod 1 and so bent as to be on the same side of the device as the hook 2. Near the ends of the holding links 7 and 8 we then provide a spacer link bar 13 secured to the holding links 7 and 8 by pivot pins 16, to hold the ends of the holding links spaced 15 apart the same distance at all times and to make the four coacting levers perform their desired operations.

Extending downwardly from the two pivoted links 4 and 5 we provide tension members 14 and 15 preferably springs as shown in the drawing and these members are secured by one end to the end of the pivoted links 4 and 5 near where the pivoted links are pivoted to the holding links and with the other ends of the tension members 20 secured to the center support rod 1 near the hook 2 so that the tension of the members will have a tendency to normally draw the pivoted links 4 and 5 down to the sides of the rod 1 and the holding links 7 and 8 folded alongside of the pivoted links 4 and 5 as shown in Figure 3 of the drawing. Thus, the hooks 2, 11 and 12 will normally be held toward any object which might be placed therebetween with the tension of the members holding the object rigid in relation thereto, and 25 the sets of links allowing for full expansion of the links to space the hooks 11 and 12 away from the hook 2 as far as possible. In this manner the hooks may be used to hold small or large folded shirts, or small or large boxes or sheets of 30 merchandise with only one device needed to hold most of the objects which a retail merchant would wish to display in his windows or on his show cases.

Onto the back side of the rod 1 we then provide a universal joint B which consists of spaced apart brackets 18 secured to the rod 1 with the universal block 19 secured therebetween by the bolt 20. The block 19 then carries the U-shaped bracket 21 secured thereto by the bolt 22 and the 45 end of the U carries the securing bolt or screw 24 which may be screwed into any desired display base or stand (not shown). It is possible to use a ball and socket joint in place of this universal and accomplish the desired result of allowing 50 55

the base to remain stationary and to allow the articles being held to be turned or tilted as desired for the window display.

When the device is used to hold a shirt the pins holding the cuffs of the shirt are removed and a board A is provided of some stiff material such as wall board and this is inserted into the shirt in the fold in the back thereof and pins are inserted into the shirt to hold it stretched to the board in smooth relation thereto at the same time not ruining the folds of the shirt or mussing it in any manner. When the shirt has been displayed as long as desired, the pins are removed, the board A withdrawn from the fold of the shirt and the cuffs of the shirt again pinned back to the shirt front and the device may then be used on another shirt and the first shirt returned to the stock.

Having thus described our invention we desire to secure by Letters Patent and claim:

- 20 1. In a device of the class described, the combination of two sets of pivotally joined coacting links secured pivotally to a center support rod; tension members to hold the links toward the support rod; and hooks on the ends of the two outer links and on the end of the support rod to engage the article to be displayed.
- 25 2. In a shirt display of the class described, the combination of a central support rod having the lower end turned up as a hook; diverging pivoted links pivotally secured together and to the top end of the support rod; other spaced apart links having their free ends bent up into hooks, said links being pivotally secured to the free ends of the diverging links; and yielding means secured 30 to the central support rod and the diverging links to draw all of the links toward the central support rod to hold articles to be displayed between the hook ends of the central rod and the spaced apart links.

3. In a display support of the class described, the combination of a single central support rod having the lower end turned up to form a hook; diverging links pivoted to the top end of said rod; article engaging links pivoted one to the end of each diverging link with the ends of the links formed into hooks to aid in holding the article; a bar spacing the free ends of the last mentioned links; and springs secured to the central support rod and to the diverging links to draw the holding hooks and the links all down toward the central support rod to hold an article between the hooks on the outer links and the central support rod. 5

4. A display device of the class described, comprising five pivotally supported links having hooks formed on the ends of three of said links to hold the article to be displayed and springs to hold the links toward the article to be held. 15

5. A display device of the class described, comprising a central support rod; diverging links pivoted to the free end thereof; holding links pivoted to the free ends of said diverging links; a universal joint to support the central rod from a suitable support in any angled position desired for display; and yielding means to hold the diverging links and the holding links toward the central support rod. 20 25

6. In a display device, the combination of a central support rod, having one end turned to form a hook; links pivotally attached to each other in pairs, having the free ends of the outer links provided with hooks and with the ends of the inner links pivotally attached to said rod; and yielding means to hold the links and central rod toward each other to draw and hold the hooks onto an article to be displayed. 30 35
